UNITED STATES PATENT OFFICE.

ROBERT D. PIKE, OF SAN FRANCISCO, CALIFORNIA.

ORE-ROASTING FURNACE.

Application filed April 13, 1921. Serial No. 460,979.

To all whom it may concern:

Be it known that I, ROBERT D. PIKE, a citizen of the United States, residing at the city and county of San Francisco and State of California, have invented certain new and useful Improvements in Ore-Roasting Furnaces, of which the following is a specification.

The present invention relates to an improved apparatus for the calcination of carbonate rocks, such for instance as calcite and magnesite, or those where the reaction is strongly heat absorbing, the object of the invention being to produce an apparatus wherein the fuel necessarily required for the calcination of the ore may be applied in such a manner that the heat of combustion shall be applied uniformly over a large area of the charge under treatment, and in such a manner that no part of the furnace shall become locally overheated. This object is accomplished by the employment of a plurality of vertically disposed fire boxes, into which the fuel is ejected in a substantially vertical direction, either from the top or bottom, and burned throughout the length of the fire boxes and relatively close to the furnace, the products of combustion and the radiant energy of the flame passing from each fire box into the furnace and over several hearths of a series of horizontally disposed hearths arranged within the furnace.

A feature of the invention for increasing the efficiency of the utilization of the heat in the fuel necessary for calcination resides in introducing into the furnace and onto the hearths thereof for intermixing with the charge under treatment, a fuel medium in the form of broken coal or coke, which is fed directly into the furnace independent of the ore charge.

For an understanding of the invention, reference should be had to the accompanying sheets of drawings illustrating the preferred embodiment of my invention, wherein:

Figure 1 is a part broken vertical sectional view of the improved mechanical roasting furnace, illustrating one form of means for the introduction of broken coal or pulverulent fuel mixture over one of the hearths of the furnace.

Figure 2 is a broken vertical sectional view disclosing the means for feeding the

fuel medium over the hearth of the furnace from the outside of the furnace shell.

Figure 3 is a broken vertical sectional view illustrative of means for the feeding of the fuel medium to the hearth of the furnace from the inside of the furnace shell.

Figure 4 is a broken detail vertical sectional view of the furnace taken on the sectional line X'-X' Figure 5 of the drawings and viewed in the direction of the arrows, said view illustrating the means for preventing the passage of air upwardly from the upper cooling hearth, while permitting the material under treatment to pass downwardly thereon.

Figure 5 is a horizontal sectional view of the furnace taken on line X-X Figure 1 of the drawings and viewed in the direction of the arrows.

Figure 6 is a broken detail horizontal sectional view taken on line Y-Y, Figure 1 of the drawings, and viewed in the direction of the arrows, said view illustrating the interior construction of the rabble arms and the connection of the same with the central rotating column of the furnace structure.

In the drawings, Figure 1 thereof, the numeral 1 is used to designate the outer shell of a stationary furnace, which is supported in the present case by the uprights 2, the said shell being interiorly provided with a refractory lining 3. Within the furnace shell is arranged a series of spaced horizontally disposed hearths, of which series the hearths 4 are those on which the material moves outwardly, dropping therefrom onto the hearth immediately below through the cutouts 5 provided therein adjacent the inner refractory lining of the shell 1. The hearths 6 of the series are those on which the material moves inwardly or toward the central rotating column of the furnace structure, the material dropping therefrom onto the hearth next below through the annular ring opening 7 thereof adjacent the wall of the central rotating column of the furnace structure. The material under treatment thus passes through the apparatus in a zig-zag path of travel from the uppermost hearth until the lowermost cooling hearth 6a is reached. These hearths surround a vertically disposed central rotating column, which in the present case is composed of two spaced concentric members 8 and 9, so disposed relative to

90

each other as to provide or leave an annular space 10 therebetween. Rotation may be imparted to the central vertical column of the furnace structure by any suitable means, as for instance through the medium of the bevel gear 11, secured to the lower extended portion 8 of the vertical column meshing with a pinion 12, which is driven by any suitable source of outside power.

By means of a blower, not shown, air under pressure is introduced through the air supply pipe 14 into the central hollow shaft through the running joint 14', the said air passing outwardly in several streams through the laterally extended passages or passageways 15 of the central column, which communicate with one of the passageways of the rabble arms 16. These rabble arms 20 are formed hollow and subdivided interiorly by means of a centrally disposed partition wall into two parallel longitudinally disposed communicating passageways *a* and *a'*. The air discharging from the central column through the passages 15 enters the passageway *a* of the rabble arms, flowing throughout the length thereof and passing into the companion parallel passageway *a'* through the end connected passage *c'* of the arms and escapes from the said arms through outlet openings 15' into the annular space 10 of the central column, Figure 6 of the drawings. The air discharging from the rabble arms into the annular space 10 of the central column moves upwardly and escapes therefrom into the pipe 18 through a running joint 17. The pipe 18 is a bent stationary one, and at its lower end communicates with the interior of the furnace structure immediately above the cooling hearth 6^a, so that the air discharging from the furnace structure is returned therein over the said lowermost cooling hearth. Each rabble arm is attached in any suitable manner to the central rotating column so as to place the parallel passages *a* and *a'* thereof in communication respectively with the air outlet and inlet passages 15 and 15' thereof, and each carries a series of depending rabble teeth 19 so disposed with reference to the charge under treatment within the furnace that when the central column and rabble arms attached thereto are rotated, the charges of material on the several hearths are moved outwardly over the hearths 4 and inwardly over the hearths 6, so that the material under treatment moves downwardly through the furnace in a zig-zag path of travel from top to bottom. It will be understood that there is a series of rabble arms associated with each hearth of the furnace.

The charge of material to be treated and fed to the apparatus is in more or less of a pulverulent form, and is fed to the fur-

nace in a regular continuous stream through the medium of any suitable form of automatic feeder, not shown, while the products of combustion and calcination leave the top of the furnace through any suitable form of outlet stack, which is not shown in the drawings.

Equally spaced around the furnace and at the outside thereof are three vertically disposed fire boxes 25, each of said boxes being provided with a burner 26 for the burning of pulverized coal or atomized oil, the said fire boxes being interiorly provided with a refractory lining, and each provided with a series of clean-out and inspection doors 26^b. The products of combustion from these fire boxes pass into the furnace over each of three hearths, at three points, through horizontally disposed ports 27, the lowermost of these three hearths being the fourth hearth from the bottom of the furnace, Figure 1 of the drawings.

Any slag or dust which collects within the bottom of the fire boxes from the burning fuel is removed periodically through the clean-out door 28, situated adjacent the bottom of each fire box. Heated air is drawn from the furnace over the second hearth 6 from the bottom thereof through the pathway 29, and conveyed upwardly into the fire box for combustion through the vertically disposed flue 29^a, entering the fire box through the inlet flues 29^b which connect the same with the upper portion of the fire box.

Provision is made for preventing the passage of air upwardly from the third hearth 4 from the bottom of the furnace through the cut-out outlet 5 thereof by extending these cut-outs downwardly through the fire-clay chute 29^c, which is provided at its lower portion with a side bottom discharge 30 toward the center of the furnace, Figure 4 of the drawings. The discharge 30 is sealed by the natural slope of the material which accumulates on the hearth 6 immediately below the said hearth 4; while the air for cooling and combustion enters the furnace over the cooling hearth 6^a, and may be taken in whole or part from the pipe 18. The bottom discharge 31 of the furnace is sealed against the passage of air by any suitable means, not shown.

The air which is preferably taken from the bent stationary pipe 18 in passing over the calcined material lying on the bottom or cooling hearth 6^a of the furnace cools it, thence flows outwardly from the furnace through the laterally disposed passageway 29 and is returned into the fire boxes 25, and thence with the products of combustion passing back into the furnace, the draft for inducing the necessary motion of air being furnished by a stack, not shown. Ordinarily twenty-five per cent more air is

admitted through the pipe 18 over the bottom or cooling hearth 6^a of the furnace than is theoretically required for the combustion of all the fuel.

5 Each fire box is preferably provided with a false bottom 25^b located immediately above the vertical flue 29^a, the area of the latter being regulated by placing or removing bricks, so that the desired amount of air 10 may be admitted over the adjacent hearth.

Where coal is to be employed as the fuel medium to be intermixed with the material under treatment, the same is broken so that practically all will pass a one-eighth inch 15 screen, and is fed in a continuous regulatable stream by any suitable form of automatic feeder into a small hopper 34, which discharges the same into the horizontally disposed feed pipe 35, Figures 1 and 2 of 20 the drawings. This pipe passes through the furnace shell and terminates in a flattened nozzle 35^a, the rear or outside end of the pipe being closed and furnished with a small centrally disposed high pressure air 25 pipe 36. The pipe 35 is provided in its side with an air inlet opening 37, which may be controlled in any suitable manner to regulate the inlet of air into the pipe 35. The high pressure air entering through the pipe 30 36 induces more air to enter through the inlet 37 than otherwise would take place, and the full quantity of this air flowing under pressure sweeps the broken coal or fuel medium discharging into the pipe 35 onto its 35 associated hearth within the furnace, where it is intermixed with the charge under treatment by means of the rabble arms. If so desired, a series of these feeders for delivering broken coal or fuel medium into the 40 furnace may be installed at one or several points over any one of the hearths of the furnace, and it will be understood that either broken coal or coke may be used as the fuel medium, and further be it understood that any suitable form of mechanical 45 means other than the one described may be employed or utilized for introducing the fuel medium into the furnace through the outside shell and onto the material for treatment.

50 By Figure 3 of the drawings, an alternative form of means for introducing the fuel to be intermixed with the material under treatment is illustrated, the same comprising a rotating hopper 38 into which the fuel is supplied from a chute 39. Within the hopper 38 is arranged or located a non-rotating vertically adjustable conical plug which is capable of being raised or lowered 55 by means of a rack and pinion 41. The hopper 38 is connected to a pipe 42 which is extended into the vertically disposed rotating column of the furnace, the lower end of the said pipe screwing into a casting 43 integral with the central rotating column and

connects through the medium of the sloping passages 44 with the interior of the furnace over one of the hearths. High pressure air is introduced into the passages 47 of the casting 43 by means of the air inlet 70 pipe 45, the passages 47 connecting with the interior of the furnace immediately below the passages 44. By this arrangement, the coal or fuel medium delivered into the hopper 38 flows downwardly through the pipe 75 42 into the passages 44 and is blown into the furnace over the hearths thereof for mixture with the material under treatment by means of the high pressure air delivered into the passages 47 from the air supply 80 pipe 45. This form of introducing the fuel medium into the furnace and onto the hearths thereof, is fully set forth and described in my co-pending application Serial No. 427,466, for improved continuous 85 method and apparatus for calcining and clinkering magnesite, to which reference is hereby made.

In the use of the described apparatus, and under the construction thereof, I have 90 found from practical experiments that about one half of the fuel required for the calcination of the ore charge is burned in the fire boxes proper and the balance introduced into the furnace and intermixed with the 95 ore charge through the auxiliary fuel supply means for delivering the same onto the hearths within the furnace. By thus reducing the amount of fuel to be burned in the fire boxes, the wear and tear on the furnace 100 brickwork is reduced materially and the life of the furnace prolonged, while the radiation losses are reduced and the broken fuel which is burned in the furnace is consumed 105 in such a manner as to directly and efficiently transfer its heat to the action of calcination. This fuel delivered within the furnace and onto the hearths therein for intermixing with the ore charge is ignited by 110 the hot gases of the furnace and by the flame injected into the furnace from the fire boxes.

If coke, braize or pulverized coke be used instead of broken coal, the same may if desired be mixed with the ore charge before 115 it is fed to the furnace instead of being delivered over one of the combustion hearths of the furnace for intermixing with the ore charge. This however, cannot be done with the coal, because the volatile constituents 120 would be volatilized on the upper hearths where the temperature would not be high enough to ignite them and they would be lost up the stack.

In the operation of the apparatus, the material to be treated as fed into the apparatus is received on the uppermost hearth of the series, and by the movement of the rabble arms is propelled by the teeth there- 125 of until the outlet passageway of the said 130

hearth is reached and is discharged on to the succeeding hearth, being propelled by the teeth of the rabble arms associated with said hearth thereover until the outlet of 5 said hearth is reached when the material falls on to the succeeding hearth, and so on successively throughout the furnace, the material being moved or propelled in a zig-zag path of travel. As the material moves 10 over the hearths within the combustion zone of the apparatus or those hearths associated with the fireboxes of the apparatus, the material is subjected to the action of the flames ejected from the fire boxes onto the 15 combustion hearths, and at the same time the fuel medium ejected into the apparatus by intermingling with the ore charge is subjected to the action of the said flames, and equally so, of the hot gasses passing up- 20 wardly through the furnace, which causes the ignition of such fuel medium. The air for the cooling of the rabble arms travels forwardly and backwardly through said arms being delivered thereto from the inner 25 shell of the rotating centrally disposed column to which the rabble arms are attached, the said cooling medium travelling upwardly and discharged within the annular passageway 10 of the centrally disposed 30 vertically rotating column and is received into the bent pipe 18, returning through said pipe into the furnace over the lowermost hearth 6^a of the furnace and which is the cooling hearth thereof, and ascending up- 35 wardly from said hearth and into the fire box through the passageways described and shown for assisting or aiding in the combustion of the fuel of the fire boxes. In this construction of the furnace, it is apparent 40 that the ore under treatment passes down- 45 wardly through the apparatus in a zig-zag course of travel over the successive hearths thereof, and during this course of travel encounters or is subjected to the counter- 50 flowing stream of the hot products of combustion. The combustion of the fuel medium ejected into furnace and onto the hearth or hearths thereof for intermixiture 55 with the ore charge, combined with the heat received from the fire-boxes, effects the calcination of the material as moved through the apparatus, and such calcination is effectively carried out on the hearths associated with the fireboxes, and which constitute the hearths within the zone of combustion.

While I have described the invention in its preferred embodiment, I do not wish to be understood as limiting myself to the 60 details of construction herein shown and described, but wish to be understood as claiming the invention as broadly as the state of the art will warrant for the production of calcined magnesite and calcite 65 more economically, and with closer tempera-

ture control than is possible with the apparatuses at present employed for such purpose.

Having thus described my invention what I claim as new and desire to secure by 70 Letters Patent of the United States is:—

1. An apparatus for the described purpose, the same comprising an outer stationary insulated vertically disposed shell, a series of superposed horizontally disposed 75 hearths arranged therein, each provided with outlets for the escape of material under treatment therefrom, mechanism associated with the hearths for propelling material thereover, a series of fire boxes situated outside of the shell and communicating with the interior thereof for injecting onto the combustion hearths thereof streams of combustion, devices for delivering from the outside of the furnace onto certain of the hearths therein a carbonaceous fuel medium for intermixing with the material under treatment, means for passing a cooling medium through the furnace, and connection for receiving said medium and returning the 80 same into the furnace adjacent the bottom thereof for cooling purposes and delivering said cooling medium into the fire boxes for purposes of combustion.

2. In an apparatus for the described purpose, the combination with the outer shell thereof, a series of superposed horizontally disposed hearths arranged therein, each provided with outlets for the escape of material therefrom, mechanism associated with the hearths for propelling thereover material under treatment, a series of fire boxes surrounding the shell and communicating with certain of the hearths therein, connections with said boxes extended from the bottom portion of the furnace for admitting thereto air for combustion, and means situated outside of the furnace shell for supplying under pressure onto certain hearths thereof a carbonaceous fuel medium for intermixing with the material under treatment.

3. In an apparatus for the described purpose, the combination with the outer shell thereof, a series of superposed horizontally disposed hearths arranged therein, each provided with outlets for the escape of material therefrom, mechanism associated with the hearths for propelling thereover material under treatment, a series of fire boxes surrounding the shell and communicating with certain of the hearths therein, and connections with said boxes extended from the bottom portion of the furnace for admitting thereto air for combustion.

4. In an apparatus for the described purpose, the combination with the outer shell thereof, of a series of superposed horizontally disposed hearths arranged therein, each provided with outlets for the escape of ma-

terial therefrom, mechanism associated with the hearths for propelling thereover material under treatment, a series of fire boxes surrounding the shell of the furnace, communications between said fire boxes and the interior of the furnace for admitting streams of combustion to certain of the hearths within the furnace, means for supplying air for cooling purposes to the hearths adjacent the bottom of the furnace, and connections for leading said air into the fire boxes for purposes of combustion.

5 In testimony whereof I have signed my name to this specification.

ROBERT D. PIKE.
